Des. 235,924
Patented July 15, 1975

235,924

COMBINED SUBMERSIBLE PUMP AND MOTOR

Hugh H. Bright, Oklahoma City, and Lee W. Davis, Del
City, Okla., assignors to Little Giant Corporation

Filed Feb. 19, 1974, Ser. No. 443,240

Term of patent 14 years

Int. Cl. D15—02

U.S. Cl. D65—1 R

— 1 —

— 2 —

FIG. 1 is a perspective view taken from the bottom, rear and one side of a combined submersible pump and motor showing our new design;

FIG. 2 is a top plan view thereof;

FIG. 3 is a front elevational view thereof; and

FIG. 4 is an elevational view taken from the side opposite that shown in FIG. 1.

The electric cord has been shown as broken away in the figures for convenience of illustration.

We claim:

The ornamental design for a combined submersible pump and motor, substantially as shown and described.
